UNITED STATES PATENT OFFICE.

HERBERT BRISTOL DWIGHT, OF HAMILTON, ONTARIO, CANADA.

DEVICE FOR TRANSFERRING RAILWAY CARS.

Application filed July 1, 1922. Serial No. 572,191.

To all whom it may concern:

Be it known that I, HERBERT BRISTOL DWIGHT, a subject of the King of Great Britain, and a resident of the city of Hamilton, in the county of Wentworth, Province of Ontario, Dominion of Canada, have invented certain new and useful Improvements in Devices for Transferring Railway Cars, of which the following is a specification.

My invention relates to improvements in devices for transferring railway cars with particular reference to the use of travelling crane equipment applicable to railway terminal yards, and the object of the invention is to increase the speed with which cars may be sorted and trains made up in a railway terminal yard; to increase the capacity for handling cars in a railway terminal of a given size and to prevent the extreme congestion which often occurs when an unusually large number of freight cars are sent to a terminal. Other objects will appear in the course of the following specification.

My invention consists essentially of the application to a railway terminal yard, having the usual series of parallel tracks, of a plurality of travelling cranes some of which are operable lengthwise of the yard and parallel with the tracks, while other of the cranes are operable crosswise of the tracks, the cranes being specially equipped to lift a car bodily off the tracks, remove it to any other desired point in the yard and redeposit it upon any other desired track location, all as hereinafter more particularly described and illustrated in the accompanying drawings in which;

Fig. 1 is a diagrammatic plan view of a railway terminal yard showing the application of my travelling crane system thereto.

Fig. 2 is a diagrammatic end elevation of a terminal yard showing the application of my invention thereto.

Fig. 3 is an elevation, partly in section, showing one of my travelling cranes in the position ready to lift a car, a rigid vertical crane arm carried thereby being broken away intermediately of its length and a car grappling arrangement carried by the lower end of this rigid arm being shown in end elevation.

Fig. 4 is an elevation of the lower por-

tion of a rigid crane arm used in my invention showing, in side elevation, a car 55 grappling frame carried at the lower end thereof.

Fig. 5 is a detached side elevation of a built up type of truck frame used on some freight cars, showing the application thereto 60 of a pad used in my invention.

Fig. 6 is a top plan view of the pad shown in Fig. 5.

Fig. 7 is a detached view showing a modified form of grappling device. 65

In the drawings like characters of reference indicate corresponding parts in the different views.

1 indicates a series of parallel railway tracks in a terminal yard, 2 being the usual 70 diagonal or ladder track having switch connections with each of the tracks 1.

3 are two overhead crane runways disposed lengthwise of the yard and parallel with the tracks 1. 75

4 are crane runways disposed crosswise of the yard and at a considerable height above the runways 3.

5 are overhead cranes running on the lengthwise runways 3, and 6 are overhead 80 cranes on the crosswise runways 4.

7 indicate railway cars, 8 being the wheels thereof and 9 the end frames of the trucks.

10 are the main carriages of the cranes 5 which operate, in the usual manner, on 85 tracks 11 mounted upon the cranes 5.

12 is a circular subsidiary carriage rotatably mounted upon a circular track 13 carried by the main carriage 10 and by the crosswise crane 6. 90

These subsidiary carriages 12 are provided with a centrally located hollow cylindrical sleeve 14 which extends above and below the carriage 12, the lower sleeve extension having a bearing in a central circular orifice 95 in the main carriage 10.

15 is a rack carried by the upper face of each of the carriages 12 and extends around the periphery thereof.

16 is an electric motor mounted upon the 100 main carriage 10 and driving a pinion 17 which meshes with the rack 15.

18 is a rigid crane arm, the upper portion 19 of which is cylindrical and is journaled within the sleeve 14 of the subsidiary 105 carriage 12.

20 is a vertically disposed rack formed on the exterior of the cylindrical portion 19, and 21 is a pinion rotatably carried by the subsidiary carriage 12 and is driven by a motor 22.

23 is a horizontal beam carried by the lower end of the rigid crane arm 19.

24 are depending hangers carried on each side of the beam 23.

10 These hangers are arranged in laterally opposed pairs, the hangers of each pair being connected by a cross member 25.

15 The hangers carry on their upper ends rollers 26 which engage runways 27 in the beam 24 so that the hangers are movable along the beam.

28 are lifting members hingedly connected at 29 to the lower ends of the hangers 24. These lifting members are provided with 20 upwardly disposed shoulders 30 which engage downwardly disposed shoulders 31 formed on bosses 32 carried by the hangers 24.

25 33 are cables connected at 34 to the lifting members 28 and pass upwardly over rollers 35 journaled in the rigid arm 18 and are connected to drums 36 which drums are rotated by a motor 37 mounted within the rigid arm 18.

30 There are two rollers 35, one being at each side of the arm 18. The cables 33 from the two lifting members 28 at one side of the beam 23 pass over the roller on the corresponding side of the arm 18.

35 Suitable guides are provided on the hangers 24 for guiding the cables 33. These are indicated at 38 (see Figs. 3 and 4) and might be in the form of pulleys, rollers, plain guide brackets or any other suitable device.

40 38 are downwardly inclined guide plates extending along the outer sides of the rails 1 and slope downwardly towards the rails (see Fig. 3).

45 39 are downwardly inclined curved plates similarly disposed along the inner sides of the rails 1.

50 These guide plates 38 and 39 are rigidly supported in any suitable manner from the road bed, as for instance upon a concrete foundation as indicated diagrammatically by the broken lines at 55 and 56 in Fig. 3.

55 40 indicates a built up type of end frame used on some freight car trucks in which the through bolts 41 project below the frame.

42 is a metal pad detachably mounted on the bottom member of the frame 40 by set screws or studs 43. This pad is provided with recesses 44 adapted to accommodate the lower projecting portions of the bolts 41 and is provided with the flat under surface 45, the purpose of which will appear herein-after.

Referring to Figure 7, an alternative form 65 of grappling device is shown, which con-

sists of a divided hook having the upper portion 46 and the lower portion 47. The hook is hingedly connected at 48 to the lower end of the hanger 24.

49 is a boss formed on the hanger and 70 engages the upper hook portion 46 and limits the upward rotation thereof.

50 and 51 are opposed engaging shoulders formed on the upper and lower hook portions respectively. 75

In this construction the cable 33 is secured at 52 to the lower hook portion 47.

53 indicates the rim of one of the car wheels 8, 54 being the web of the wheel.

Suitable brakes (not shown) would be 80 provided for all motors used.

The construction and operation of my invention is as follows:

When it is desired to remove a car from one track location to another within the 85 yard, one of the cranes 5 is brought to its proper position above the car, and the main carriage 10 moved so that it is over the car to be lifted.

The cables 33 are then slackened by means 90 of the motor 37 so that the lifting members 28 hang freely.

The rigid vertical arm 18 is then lowered by means of the motor 22, rack 20 and pinion 21 so that the hangers 24 pass downwardly 95 on each side of the car.

As the arm descends the freely hanging members 28 strike the inclined guide plates 38 and are automatically raised into their correct position to engage under the trucks 100 of the car. When in this position the cables 33 are tightened.

The inclined plates 38 thus constitute means for guiding the grappling elements into the correct operative engagement with 105 the running gear as the crane descends.

Upon the raising of the arm 18 the car is bodily lifted off the rails 1 and since the lifting members 28 engage under the trucks it will be evident that the entire car, including all the running gear thereof, is lifted and while in the suspended position no disengagement of any of the running gear is possible.

The car is then transferred to the desired 115 new track location and the arm 18 lowered.

As the car is lowered if it is not positioned exactly centrally above the track the wheels 8 will engage the inclined guide plates 38, and will be automatically guided thereby 120 into their correct position upon the rails.

The plates 39 on the inside of the rails will also assist in properly positioning the car as it approaches the rails in its descent.

It will thus be seen that the guide plates 125 38 constitute a means of automatically guiding the grappling mechanism into its correct engagement with the car when the crane is descending to pick up a car and also when the car is being redeposited upon the tracks 130

these plates 38 and also the plates 39 form a means of automatically guiding it to its correct position on the rails.

In this way a great saving in time will be effected since it is only necessary for the crane operator to gauge the position of his crane approximately and it is not necessary that time and labor be wasted in coupling up the grappling mechanism.

10 A feature of my construction is the incorporation of a turntable within the crane and from an examination of Figure 3, it will be noted that, when the car is suspended, the rigid vertical arm 18 may be rotated by 15 means of the motor 16, pinion 17 and rack 15 so that the car may be turned end for end.

In transferring cars by the method described it is essential that provision be made 20 for preventing the undue swinging of the suspended car and this is entirely overcome in my invention by the manner in which the vertical arm is connected to the crane.

The sleeve 14 in which the upper end 25 of the crane arm is journalled forms a means of preventing all swinging of the arm and therefore the danger of accidents due to swinging of a suspended car is eliminated.

30 Ordinarily the lifting members 28 will extend under the flat end surface of the truck frame but in certain types such as that illustrated in Figure 5 there are bolts extending through the frame in which cases 35 it will be advisable to fit a pad such as the pad 42.

The operation of the modified grappling arrangement shown in Fig. 7 will be apparent.

40 When lowering the crane over a car the cables 33 will be slackened as already described with the previous construction, permitting the divided hooks to hang freely, and at the proper time these hooks will 45 be placed in their operative engagement with the car wheels by hand and upon the tightening of the cables 33 the hooks will securely grip the wheels under the rim 53.

The car is lifted by raising the rigid 55 vertical arm as already described.

The cross cranes 6 must of course be at such a height that a car can be lifted over the other cars and the crane runways which are parallel to the tracks. In order 55 to permit operation of these crosswise cranes the tracks under the crosswise runways should be kept clear so that there will be space for the lengthwise cranes to deposit cars within the sphere of the crosswise 60 cranes.

These cross cranes would be used in shifting cars from the sphere of one lengthwise crane to another.

The cranes 5 and 6 and the main crane 65 carriages 10 would be electrically driven

in the ordinary manner and as this forms no part of my invention the details of this drive have not been illustrated or described.

A further feature of my construction is that due to the use of an absolutely rigid 70 crane arm, it will be possible for the cranes to be used as locomotives for simply pushing cars along the tracks and thus the cranes will of themselves be able to completely make up a train without assistance 75 from a locomotive. A crane which lifts by means of cables is not rigid enough to operate quickly and satisfactorily as a locomotive or to stop a car quickly and accurately. 80

The application of my system to a terminal yard will not in any way interfere with the operation of the ordinary method of switching cars since the tracks are not interfered with. This permits the removal 85 of a car track location without interfering with independent switching operations which may be going on on that track by a locomotive in the ordinary way.

It is to be noted that with my device 90 the car wheels are maintained parallel to the rails while the car is suspended.

From the foregoing it will be evident that I have devised valuable improvements in 95 equipment for transferring railway cars which should greatly increase the capacity of railway terminal yards and greatly expedite the sorting of cars and the making up of trains.

Various modifications may be made in 100 my invention without departing from the spirit of the invention or the scope of the claims and therefore the forms shown are to be taken as illustrative only and not in a limiting sense. 105

For instance, while I have illustrated and described a particular car grappling mechanism, various modifications might be made in the exact details of construction.

Also it might be desirable in certain installations to employ gantry cranes in place of the overhead type above described in which case the construction would necessarily have to be slightly altered to suit this type of crane. 110

Also it is to be understood that the lifting members 28 might be arranged to limit longitudinal movement of the car due to inertia of the car upon the starting and stopping of the crane. 115

What I claim as my invention is:

1. In a device for transferring railway cars the combination with a travelling crane adapted to lift a car bodily off the supporting rails, of car grappling elements carried 125 by the crane and engageable with the running gear of a car to be lifted, inclined guide plates placed parallel with and on the outer sides of the rails, said plates being situated adjacent to and inclined down- 130

wardly towards the rails and adapted to engage the grappling elements as the crane is lowered to pick up a car.

2. In a device for transferring railway cars the combination with a travelling crane adapted to lift a car bodily off the supporting rails, of car grappling elements carried by the crane and engageable with the running gear of a car to be lifted, inclined 10 guide plates placed parallel with and on the inner sides of the rails, said plates being situated adjacent to and inclined downwardly towards the rails and adapted to engage the running gear of the car as the car is lowered to be redeposited upon the rails.

3. In a device for transferring railway cars the combination with a travelling crane adapted to lift a car bodily off the supporting rails, of car grappling elements 20 carried by the crane and engageable with the running gear of a car to be lifted, inclined guide plates placed parallel with and on each side of the rails, said inclined plates situated adjacent to the rails and being inclined downwardly towards the rails, the guide plates on the outer sides of the rails adapted to engage the grappling elements as the crane is lowered to pick up a car and the guide plates on the inner sides 30 of the rails adapted to engage the running gear of the car as the car is lowered to be redeposited upon the rails.

4. A device for transferring railway cars comprising a crane, a rigid vertical arm

slidably carried in vertical guides on the 35 crane, means for raising and lowering the arm vertically in its guides, means for rotating the arm about its vertical axis, and car grappling means carried at the lower end of the rigid arm, said grappling means 40 engageable with a fixed portion of the truck of a car to be lifted.

5. A device for transferring railway cars comprising a crane, a rigid vertical crane arm carried thereby and movable up and 45 down in vertical guides, a horizontal beam carried at the lower end of the rigid arm, depending hangers associated with the horizontal beam, said hangers arranged in a plurality of pairs, each pair composed of a 50 hanger at each side of the beam and adapted to lie at opposite sides of a car to be lifted, the pairs being movable longitudinally of the beam, lifting members hingedly carried at the lower ends of 55 the hangers and engageable with the running gear of a car to be lifted, engaging bosses formed on the hangers and lifting members for limiting the upward rotation of said lifting members, means for maintaining the aforesaid bosses in their engaged positions and means for raising and lowering the rigid vertical arm.
